Int. Cl. D8—03

U.S. Cl. D8—98

FIG. 1 is a top plan view of a handle for removable putty knife and scraper blades and the like showing my new design;

FIG. 2 is a bottom plan view thereof;

FIG. 3 is a left side elevational view thereof;

FIG. 4 is an end view thereof showing the end of the handle where the blade is inserted;

FIG. 5 is an opposite end view thereof; and

FIG. 6 is a cross-sectional view taken along the lines 6—6 of FIG. 1.

The broken line showing of a portion of a blade in FIGS. 1 and 6 is for illustrative purposes only.

I claim:

The ornamental design of a handle for removable putty knife and scraper blades and the like, substantially as shown.
